SAFETY GARMENT HANGER

Jacob Hazai Beckmann, New York, N. Y.

Application March 31, 1938, Serial No. 199,140

8 Claims. (Cl. 223—93)

This invention relates to new and useful improvements in a safety garment hanger.

More specifically, the invention proposes the construction of a safety dress or garment hanger characterized by a hanger of conventional construction having a support bar and a hook attached to the center thereof and upon which fingers are supported for engaging the ends of the support bar to clamp portions of a garment thereon to prevent the garment from slipping from the hanger.

Still further it is proposed to provide the fingers at their inner ends with a bifurcated end, one portion of which is adapted to engage a leaf spring supported upon said support bar and the other end of which is adapted to be used as a handle for urging the fingers into operative positions against the action of the leaf springs.

Another object of this invention is to provide the outer ends of the fingers with elements for engaging the garment supported on the support bar for frictionally holding it in position thereon.

A further object of this invention is to provide the spring with a plurality of lateral sections of different stiffnesses and to laterally shiftably support the fingers so that they may be selectively engaged with one of said sections for controlling the engagement of the end of said finger against the garment on said support bar. For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is an elevational view of a safety garment hanger constructed according to this invention.

Fig. 2 is a sectional view taken on the line 2—2 of Fig. 1.

Fig. 3 is a sectional view taken on the line 3—3 of Fig. 2.

Fig. 4 is a view looking in the direction of the line 4—4 of Fig. 1.

Fig. 5 is a sectional view on the line 5—5 of Fig. 4.

Fig. 6 is a view similar to Fig. 4 but illustrating a modification of the invention.

Fig. 7 is a sectional view on the line 7—7 of Fig. 6.

Fig. 8 is an elevational view of a still further modified form of tip for said finger.

Fig. 9 is a view looking in the direction of the line 9—9 of Fig. 8.

Fig. 10 is a plan view of a modification of the safety dress hanger.

Fig. 11 is a sectional view on the line 11—11 of Fig. 10.

Fig. 12 is a perspective view of a modified form of spring per se.

Fig. 13 is a perspective view of one of the fingers per se.

The safety garment hanger, according to this invention, includes a support bar 10 for engaging the shoulder portions of a garment. This support bar is constructed from wood or similar material.

A hook 11 is attached to the center of the bar 10. The hook 11 is constructed from a piece of relatively stiff wire which has one of its ends extending axially through the support bar 10 at the center thereof and which is provided at its other end with a rounded portion 11a which is adapted to engage a support in the usual manner.

A small housing 12 is mounted on the support bar and engages the lower extremity of the hook 11. The housing 12 is constructed from a piece of sheet metal or other material and it is substantially rectangular in shape and is formed at one of its sides with downwardly extending lugs 12a by which it is securely attached to the support bar 10. The top wall of the small housing 12 is formed with an opening 12b through which the hook 11a extends.

A leaf spring 13, substantially oval in shape, is mounted within the housing 12 and has an opening 13a through which the lower extremity of the hook 11 passes, and has its end portions engaging the sides of the lower extremity of the hook. The leaf spring is constructed from a piece of spring steel and is bent into substantially oval shape and has its free ends 13b bent at right angles thereto so as to engage flush against the lower extremity of the hook 11.

Fingers 14 for engaging the support bar 10 to clamp portions of a garment thereon to prevent the garment from slipping off the hanger have one of their ends pivotally mounted on the housing. Pins 15 extending through the ends of the housing 12 pass through openings 14a formed in the ends of the fingers 14 for pivotally supporting the same. The end of the fingers 14 adjacent their pivoting points are bifurcated and have a portion 14b engaging against the leaf spring 13 for holding the fingers 14 in operative or inoperative positions. The other

ends 14^c of the bifurcated ends extend through slots 12^c formed in the top wall of the small housing 12 and are adapted to be used as handles for pivoting said fingers to their operative or inoperative positions.

The other end of the fingers 14 are flattened and have felt members 16 securely attached thereto for engaging against the outer portion of the shoulder portion of the garment for frictionally maintaining the garment in position upon the support bar 10 .

The operation of this device is as follows:

For engaging a garment upon the support bar 10 the ends 14^c of the fingers are grasped and urged towards the hook 11 for moving the fingers 14 to their operative position as shown by the full lines on the right hand side of Fig. 1. The garment is then engaged upon the support bar 10 in the customary manner and the ends 14^c of the fingers are urged away from the hook 11 to cause the fingers 14 to be moved to their operative positions in which the felt members 16 will engage the garment for frictionally holding it in position thereon to prevent it from sliding therefrom.

According to the modification shown in Figs. 6 and 7 the ends of the fingers $14'$ are formed with rubber elements $16'$ which are adapted to encircle the ends of the fingers $14'$ and engage against the shoulder portion of a garment for frictionally maintaining it in position on the support bar. In other respects this form of the invention is similar to the previous form.

According to the modification shown in Figs. 8 and 9 the fingers $14''$ are formed at their outer ends with bifurcated ends 14^d which are adapted to have small wheels $16''$ rotatively supported thereon. These wheels $16''$ are rotatively supported upon pins 17 extending between the ends 14^d . The outer periphery of the wheels $16''$ are formed with serrations 16^a which are adapted to assist in frictionally maintaining the garment in position on the support bar 10 . In other respects this form of the invention is similar to the previous forms.

According to the modification shown in Figs. 10-13 inclusive the spring $13'$ has its active portions divided into a plurality of lateral sections 13^c , 13^d and 13^e all of different stiffnesses. The fingers 14 are laterally shiftable relative to the housing so that the end 14^b may be selectively engaged with the different sections of the spring $13'$ for varying the gripping actions of these fingers. The means for forming the sections of different stiffness comprise reinforcing elements 13^{dd} attached to the inner face of the sections 13^d for increasing the stiffness of these sections over the section 13^c . The ends of the sections 13^d also butt against the lower extremity of the hook 10 for stiffening these sections to a greater degree than the sections 13^c and 13^e .

The section 13^e has elements 13^{ee} attached to its inner face for increasing the stiffness of this section relative to the section 13^c . Thus the sections 13^c are weakest, the sections 13^e are next strongest and the sections 13^d are strongest. The fingers 14 are adapted to be shifted to the positions illustrated by the dot and dash lines 14^d shown in Fig. 10 for controlling the engagement of these fingers with the garment supported upon the support bar 10 . The outer faces of the sections 13^c , 13^d and 13^e are convexed slightly inwards and are adapted to be engaged by the end 14^b of the fingers 14 for maintaining the

fingers in adjusted positions upon the pivot pin 15 .

The operation of this form of the device is as follows:

The garment is engaged upon the support bar 10 in a manner similar to that described relative to Figs. 1-5, but in the event that the garment is too heavy and there is not sufficient pressure on the ends of the fingers 14 to maintain the garment in position upon the support bar 10 , the fingers 14 may be shifted to engage either of the stiffer fingers 13^d or 13^e for properly supporting the garment on the support bar 10 .

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A safety garment hanger, comprising a support bar for engaging the shoulder portions of a garment, a hook attached on the center of said bar, a small housing mounted on said support bar and encasing the lower extremity of said hook, a leaf spring of oval shape mounted within said housing and said leaf spring having an opening in its center through which the lower portion of said hook passes and having its end portions engaging the sides of said lower portion of the hook, fingers for engaging the support bar to clamp portions of a garment thereon to prevent the garment from slipping off the hanger, and said fingers being pivotally mounted on said housing and having bifurcated inner ends, one of the portions of which engage said leaf spring for holding the fingers raised or lowered, and the other portions of which project from said housing and form handles by which the fingers may be moved.

2. A safety garment hanger, comprising a support bar for engaging the shoulder portions of a garment, a hook attached on the center of said bar, a small housing mounted on said support bar and encasing the lower extremity of said hook, a leaf spring of oval shape mounted within said housing and said leaf spring having an opening in its center through which the lower portion of said hook passes and having its end portions engaging the sides of said lower portion of the hook, fingers for engaging the support bar to clamp portions of a garment thereon to prevent the garment from slipping off the hanger, and said fingers being pivotally mounted on said housing and having bifurcated inner ends, one of the portions of which engage said leaf spring for holding the fingers raised or lowered, and the other portions of which project from said housing and form handles by which the fingers may be moved, said hook being formed from a piece of stiff wire and having one of its ends connected with said support bar at the center thereof and the other of its ends formed into the shape of a hook for engaging a support element.

3. A safety garment hanger, comprising a support bar for engaging the shoulder portions of a garment, a hook attached on the center of said bar, a small housing mounted on said support bar and encasing the lower extremity of said hook, a leaf spring of oval shape mounted within said housing and said leaf spring having an

- opening in its center through which the lower portion of said hook passes and having its end portions engaging the sides of said lower portion of the hook, fingers for engaging the support bar 5 to clamp portions of a garment thereon to prevent the garment from slipping off the hanger, and said fingers being pivotally mounted on said housing and having bifurcated inner ends, one of the portions of which engage said leaf 10 spring for holding the fingers raised or lowered, and the other portions of which project from said housing and form handles by which the fingers may be moved, said hook being formed from a piece of stiff wire and having one of its 15 ends connected with said support bar at the center thereof and the other of its ends formed into the shape of a hook for engaging a support element, said housing being constructed from a piece of sheet metal or similar material and being formed on its bottom wall with downwardly extending lugs by which it is securely 20 attached to the said support bar and having an opening formed in its top wall through which the lower end of said hook passes.
- 25 4. A safety garment hanger, comprising a support bar for engaging the shoulder portions of a garment, a hook attached on the center of said bar, a small housing mounted on said support bar and encasing the lower extremity of said hook, a leaf spring of oval shape mounted within said housing and said leaf spring having an opening in its center through which the lower portion of said hook passes and having its end portions engaging the sides of said lower portion of the 30 hook, fingers for engaging the support bar to clamp portions of a garment thereon to prevent the garment from slipping off the hanger, and said fingers being pivotally mounted on said housing and having bifurcated inner ends, one of the portions of which engage said leaf spring 35 for holding the fingers raised or lowered, and the other portions of which project from said housing and form handles by which the fingers may be moved, said leaf spring being constructed from a piece of spring steel and having its free ends 40 turned inwards so as to lay flush against the sides of said hook.
- 45 5. A safety garment hanger, comprising a support bar for engaging the shoulder portions of a garment, a hook attached on the center of said bar, a small housing mounted on said support bar and encasing the lower extremity of said hook, a leaf spring of oval shape mounted within said housing and said leaf spring having an 50 opening in its center through which the lower portion of said hook passes and having its end portions engaging the sides of said lower portion of the hook, fingers for engaging the support bar to clamp portions of a garment thereon to prevent the garment from slipping off the hanger, and said fingers being pivotally mounted on said housing and having bifurcated inner ends, one of the portions of which engage said leaf spring 55 for holding the fingers raised or lowered, and the other portions of which project from said housing and form handles by which the fingers may be moved, said leaf spring having a plurality of lateral sections of different stiffness, and said fingers being laterally shiftable relative to said housing to have the ends thereof engage the different sections of the spring for varying the gripping action of the fingers.
- 60 6. A safety garment hanger, comprising a support bar for engaging the shoulder portions of a garment, a hook attached on the center of said bar, a small housing mounted on said support bar and encasing the lower extremity of said hook, a leaf spring of oval shape mounted within 65 said housing and said leaf spring having an opening in its center through which the lower portion of said hook passes and having its end portions engaging the sides of said lower portion of the hook, fingers for engaging the support bar to clamp portions of a garment thereon to prevent the garment from slipping off the hanger, and said fingers being pivotally mounted on said housing and having bifurcated inner ends, one of the portions of which engage said leaf spring 70 for holding the fingers raised or lowered, and the other portions of which project from said housing and form handles by which the fingers may be moved, said leaf spring having a plurality of lateral sections of different stiffness, and said fingers being laterally shiftable relative to said housing to have the ends thereof engage the different sections of the spring for varying the gripping action of the fingers, said means for stiffening said sections comprising elements of different stiffness attached to the inner faces of said sections for increasing the stiffness of one section over the stiffness of its next adjacent section.

JACOB HAZAI BECKMANN.
